UNITED STATES PATENT OFFICE

EDWARD M. LAING, OF HIGHLAND PARK, ILLINOIS

GOLF-BALL CLEANER

Application filed April 12, 1928. Serial No. 269,512.

This invention relates to a golf ball cleaner, and more particularly to an improved apparatus by means of which a person may scrub a golf ball easily and efficiently, without unduly soiling the hands or clothing.

One object of the invention is to provide an apparatus embodying a receptacle for holding water, in which is positioned a pair of opposed brushes, and means for moving a golf ball back and forth between the brushes in such a manner that all portions of the brushes are utilized.

Another object is to provide an apparatus of this type so assembled that the accumulated dirt can be quickly removed.

Another object is to provide means for minimizing the splashing of water from the receptacle.

Other objects and advantages of this invention will be more apparent from the following detailed description of one approved form of the apparatus.

In the accompanying drawings:

Fig. 1 is a side elevation of the assembled apparatus.

Fig. 2 is a central vertical section, taken substantially on the line 2—2 of Fig. 1.

Fig. 3 is a vertical section taken substantially on the line 3—3 of Fig. 2.

Fig. 4 is a plan view of one end portion of the apparatus, illustrating one of the flat closures.

Fig. 5 is a view similar to Fig. 2, showing a modification.

The device comprises an outer receptacle 1, usually formed of sheet metal, and of substantially the rectangular proportions illustrated in the drawings. The edges of the upper open end of this receptacle 1 may be crimped over or wire bound, as indicated at 2, in order to reinforce and strengthen the receptacle. The receptacle 1 is supported in an upright position at a convenient height in any suitable manner. As here shown, brackets 3, secured in vertical position by bolts 4 to the top of posts 5, are adapted to be received in sockets formed by metal straps or loops 6 secured to one side of the receptacle 1. Set screws 7 mounted in straps 6 are adapted to be tightened against the brack-

ets 3 and thus removably secure the apparatus in position at the top of posts 5.

In the form of the invention shown in Figs. 1, 2, and 3 a second inner receptacle or brush-holder 8 consists of a metal outer shell, somewhat shallower than receptacle 1 and having an arcuate bottom 9 formed with a plurality of perforations 10 so that water or other liquid held in receptacle 1 may pass freely into and through the inner receptacle 8, and dirt from within receptacle 8 may be forced through perforations 10 into the outer receptacle 1. Preferably receptacle 8 is provided at the top with an outwardly and downwardly curved flange 11 adapted to rest upon the upper edges 2 of receptacle 1 and thus support the inner receptacle or brush holder in its normal position. A pair of spring locks or latches 12, mounted one on each side wall of receptacle 1, are adapted to be sprung into and out of mating openings in the two receptacles so as to removably lock the brush holder in position.

A pair of brushes 13, preferably of arcuate form, as shown in Fig. 3, are secured against the opposite side walls of receptacle 8 by any suitable means, such as screws 14. The inner opposing ends of the bristles 15 of the two brushes 13 are spaced apart a distance substantially less than the diameter of a golf ball, such as indicated at 16.

The central portions of the backs of brushes 13 extend upwardly at the center, as indicated at 17, these upward extensions being connected by a bolt 18 on which is intermediately pivoted the ball-holding member 19. Suitable blocks or spacing members 20 mounted between the extensions 17 of brushes 13, serve to hold the member 19 in a central position along the pivot shaft or bolt 18. The upper end of member 19 is formed as a handle 21 whereby the member may be conveniently swung from side to side. An elongated slot 22 is formed in the lower portion of member 19, this slot being slightly wider than the diameter of a golf ball. The slot is inclined at an angle of substantially 45° to the longitudinal center line of member 19, or to the arcuate path of travel of the lower end of member 19. The elongated slot 22 is of suf-

ficient length to extend substantially from one side to the other of the brushes 13, all as illustrated most clearly in Fig. 3.

A flap or closure 23 is pivoted at 24 adjacent each end of the inner receptacle 8. Springs 25 normally holds these flaps down so as to cover or enclose the end portions of the receptacles. However, when the ball-holding member 19 is swung down to the position, such as illustrated in dotted lines in Fig. 3, the flap 23 at the opposite end of the receptacle will be swung up to the position indicated in dotted lines to permit the ball-holding portion of member 19 to be moved up out of the receptacle. When the member 19 is again swung upwardly, the flap 23 will automatically close.

In operation the parts are assembled as shown in the drawings, and the receptacles 20 1 and 8 filled to a convenient height with water. When the member 19 is swung down to one end or the other of its arcuate path of travel, as illustrated in dotted lines in Fig. 3, a golf ball 16 may be placed within 25 the slot 22. The member 19 is now oscillated back and forth, although preferably not to the extreme dotted line positions, so that the ball 16 will remain continuously between the brushes 13. It will be noted that as the 30 lower end of member 19 is moved downwardly (for example from the dotted line to the full line position, Fig. 3), the inclination of slot 22 will cause the ball 16 to work down toward the lower end of the slot. When the 35 member 19 is swung in the opposite direction, the inclination of slot 22 will cause the ball 16 to move upwardly toward the other end of the slot. Consequently, as the member 19 is oscillated back and forth between the 40 brushes, the ball 16 will move alternately from one end of slot 22 to the other, thus utilizing substantially all portions of the brushes during this scrubbing process. The ball will roll freely within slot 22 in all directions, so 45 that all portions of the ball will be quickly scrubbed. It will be noted that as soon as the ball-holding end of member 19 has been moved down into the receptacles, the flap closure 23 at that end of the device will immediately close so as to prevent the splashing 50 of water from the receptacles. Both slots remain closed continuously until the member 19 is swung down far enough to one side or the other to bring the lower ball-holding portion of the member up out of the receptacle. At such a time, the ball may be removed or 55 inspected to see if it is sufficiently clean.

The greater portion of the dirt that is removed from the balls will eventually pass 60 through perforations 10 (which may be quite large) into the outer receptacle 1. At suitable intervals of time, the scrubbing assembly consisting of the inner receptacle or brush-holder 8, and the brushes and ball-holding member 65 19 carried thereby, may be removed from re-

ceptacle 1 by simply releasing the spring latches 12. This assembly may be easily cleaned by simply holding the same under running water. The accumulated dirt may now be removed from the open receptacle 1, and if necessary this cleaning process may be facilitated by removing the receptacle 1 from the supporting posts 5. This is easily accomplished by simply loosening the set screws 7.

In the modified form shown in Fig. 5, the device is simplified by eliminating the inner receptacles 8. The two brushes are connected by a plurality of bolts, one of which is indicated at 26, and spacing members 27 serve to hold the brushes apart at the proper distance. Smaller spacing members or shims 28 may also be used, and by removing one or more of these shims the brushes may be brought closer together to allow for wear of the brushes. The entire brush-holding assembly is supported within the upper portion of receptacle 1 by means of the outwardly curved hooks or flanges 29 secured to the backs of the brushes. The flaps or closures 23 will be pivotally mounted between the ends of the brushes as in the first described form. The operation of this form of the invention is in all respects the same as that of the first described form.

If desired, the inner scrubbing assembly (of either form above described) can be hinged at one end within the outer receptacle and provided with a suitable clasp at the other end, instead of being entirely removable as in the preferred forms described. It will be apparent that many other changes in design and proportions may be made without departing from the principles of the invention as set forth in the following claims.

I claim:

1. A golf ball cleaner comprising a receptacle for holding liquid, a pair of opposed brushes mounted within the receptacle and a member pivoted intermediately of its length on a horizontal axis above the receptacle and formed with an upwardly extending handle portion, and a downwardly extending portion of less thickness than the diameter of a golf ball adapted to swing between the brushes, the downwardly extending portion of the member being formed with an aperture for loosely receiving a golf ball.

2. A golf ball cleaner comprising a receptacle for holding liquid, a scrubbing assembly and means for removably supporting the assembly within the upper portion of the receptacle, the scrubbing assembly consisting of a pair of opposed brushes, means securing the brush-backs together in spaced parallel relation, a flat member of substantially less thickness than the diameter of a golf-ball intermediately pivoted between the upper central portion of the brushes, the upwardly extending portion of the member being in the form of a handle and the lower portion which swings between the brushes being formed

with an aperture to loosely receive the golf-ball.

3. A golf ball cleaner comprising a receptacle for holding liquid, a scrubbing assembly and means for removably supporting the assembly within the upper portion of the receptacle, the scrubbing assembly consisting of a pair of opposed brushes, means securing the brush-backs together in spaced parallel relation, a flat member of substantially less thickness than the diameter of a golf-ball intermediately pivoted between the upper central portion of the brushes, the upwardly extending portion of the member being in the form of a handle and the lower portion which swings between the brushes being formed with an aperture to loosely receive the golf ball, and a pair of spring-held flap closures pivoted one at each end of the top of the scrubbing assembly and adapted to be lifted by the ball-holding member when it is swung up from between the brushes.

4. A golf ball cleaner comprising a receptacle for holding liquid, a scrubbing assembly consisting of a pair of opposed brushes of downwardly projecting arcuate contour, the central portions of the brush-backs projecting upwardly, a plurality of bolts connecting the brush-backs, spacers on the bolts between the brushes to hold the brushes in spaced parallel relation, a flat member of substantially less thickness than the diameter of a golf ball intermediately pivoted between the upwardly extending central portions of the brush-backs, the upper portion of the member forming a handle and the lower portion which swings between the brushes being formed with an aperture to receive the golf ball, and means for suspending the scrubbing assembly within the upper portion of the receptacle.

5. A golf ball cleaner comprising a receptacle for holding liquid, a pair of opposed brushes mounted within the receptacle and a member pivoted intermediately above the receptacle and formed with an upper handle portion, and a lower portion of less thickness than the diameter of a golf ball adapted to swing between the brushes, the member being formed with an aperture for loosely receiving a golf ball, and a pair of flap closures for the opening in the upper portion of the receptacle, said closures positioned to be lifted by the lower ball-holding portion of the member as it is swung up out of the receptacle.

EDWARD M. LAING.
